UNITED STATES PATENT OFFICE.

NELLIE L. BUCKMAN, OF SANTA ANA, CALIFORNIA.

QUICKLY-DETACHABLE VALVE CAP.

Application filed December 23, 1925. Serial No. 77,225.

This invention relates to improvements in valve caps and particularly to dust caps adapted to be applied to tire valve stems.

An object of this invention is to provide a valve dust cap which can be applied by merely forcing the cap downwardly over the valve stem and which will automatically engage and firmly grip the valve stem so that it cannot be loosened or lost.

10 A further object of the invention is to provide a quickly attachable and detachable valve dust cap as above described, which upon slight rotation will close and effectively seal the end of the valve stem to prevent any leakage.

15 With the foregoing and other objects in view which will be made manifest in the following detailed description and specifically pointed out in the appended claims, reference is had to the accompanying drawings for an 20 illustrative embodiment of the invention, wherein:

Figure 1 is a partial side elevation of a portion of a vehicle wheel to which the improved valve cap is shown as applied, the valve cap being shown in vertical section,

25 Fig. 2 is a vertical section through the valve cap when in its removed or detached position,

Fig. 3 is a side elevation of the valve cap,

30 Fig. 4 is a vertical section through the shell constituting a part of the improved valve cap,

Fig. 5 is a top plan view of the movable member which is disposed within the shell,

Fig. 6 is a side elevation of the movable member,

35 Fig. 7 is a bottom plan view of the movable member,

Fig. 8 is a vertical section taken on the line 8—8 of Fig. 5,

40 Fig. 9 is a vertical section through the rubber washer or gasket disposed within the movable member.

Referring to the accompanying drawings wherein similar reference characters designate similar parts throughout, the improved valve cap consists of a cylindrical shell 10 having its top closed and its bottom open. The interior surface of the shell is cylindrical, and adjacent its bottom there is formed an annular recess 11, which may be formed by upsetting the bottom of the shell. Within the shell there is disposed a movable member consisting of a disc 12 which has downwardly extending resilient arms 13 arranged about its edges. These resilient arms are separated from each other, as indicated at 14, and ad-

jacent their upper ends they are of reduced width, as indicated at 15, so that their resiliency or spring may be increased. On the bottom of each of the arms 13 there are formed inwardly extending jaws 16 which cooperate to present an interior annular surface of a diameter substantially equal to the diameter of the reduced portion R of the valve stem S. On the exterior or outer surface of each of the arms 13 there is formed a projection 17, and each of these projections is capable of being received within the interior annular recess 11. The opposed faces of the jaws 16 are threaded, as indicated at 18, and these threads are complementary to the threads on the reduced portion R of the valve stem. Between the disc 12 and the inwardly extending jaws 16 there is positioned a rubber washer or gasket 19, preferably having a depending annular flange 20 positioned against the interior surfaces of the arms 13. On the bottom of the gasket 19 at its center there is preferably arranged a recess 21 capable of receiving the end of the stem or the pin of the valve disposed within the valve stem S.

The operation of the improved valve cap is as follows: When the valve cap is detached or removed from the valve stem S, the movable member assumes the position shown in Fig. 2, the arms 13 springing outwardly and causing the projections 17 to enter the recess 11. In this manner the jaws are separated from each other a sufficient distance to permit the reduced portion R of the valve stem to enter between them. In applying the valve cap to the valve stem it is so positioned as to cause the reduced portion R of the valve stem to enter between the jaws and engage the bottom of the gasket 19. By forcing the shell 10 downwardly, the movable member will be caused to rise within the shell 10, and as the projections 17 slide out of the recess 11, they cause the jaws to contract and engage upon the reduced portion R of the valve stem. The initial movement of the projections 17 when slipping out of the recess 11 causes the contraction of the jaws, and any further sliding of the movable member upwardly within the shell does not change the position of the jaws; in other words, the jaws will be continually maintained in engagement with the reduced portion R of the valve stem while the shell is being caused to slide downwardly over the valve stem after this first initial movement. In this manner the valve cap can be applied to the valve by merely forcing the shell down-

wardly over the valve stem. If it is desired to prevent any leakage out of the valve stem, the shell may be rotated after it has been applied. The threads 18 meshing with the 5 threads on the reduced portion R screw the movable member downwardly on the valve stem and thus cause the upper edge of the valve stem to firmly engage the under side of the gasket 19, and thus prevent any leakage. If the stem or pin of the valve within 10 the valve stem projects slightly, it is receivable within the recess 21, so that it will not be depressed to move the valve off the seat. It will be found that a half or a three quarter 15 revolution of the shell is sufficient to cause the firm engagement between the valve stem and the gasket. The friction of the arms 13 against the interior surface of the shell is sufficient to cause the movable member to be rotated with the shell.

In removing the valve cap, it is merely necessary to lift the shell 10, causing the movable member to slide downwardly within it and when it reaches a predetermined position, 25 in this instance the bottom of the shell, the arms 13 expand causing the projections 17 to enter the recess 11, thus expanding the jaws and permitting the removal of the cap. The expansion of the arms 13 causing the projections 30 17 to enter the recess 11 also serves as a lock for preventing the movable member from dropping out of the shell.

It will be understood that various changes may be made in the detail of construction 35 without departing from the spirit or scope of the invention as defined by the appended claims.

I claim:

1. In a quickly detachable valve cap, a tubular member, a valve stem closure confined 40 and slidable in said tubular member, said closure including a disc and integral resilient arms, and said tubular member having therein an annular recess engageable by said resilient arms.

2. In a valve cap, a shell, a closure member disposed and movable within said shell and capable of assuming positions adjacent the bottom or top of said shell, and resilient jaws engageable with a valve stem carried by said member, said member being adapted to be engaged by the top of a valve stem and held in position when said shell is forced downwardly thereover, said shell presenting interior surfaces adapted to engage upon said 50 jaws and force the same into engagement with the sides of said valve stem when said shell is forced thereover.

3. In a valve cap, a shell having an interior annular recess formed therein adjacent the bottom thereof, a disc disposed within the shell, depending resilient arms on said disc, and projections on said arms adapted to enter said recess, the lower ends of said arms being bent inwardly at substantially right angles to provide jaws engageable on the sides of a valve stem, whereby said disc will be held by said stem against longitudinal movement when said shell is forced thereover and said jaws will be forced into engagement with said 65 valve stem by said projections when the latter are forced out of said recess.

In testimony whereof I have signed my name to this specification.

NELLIE L. BUCKMAN.
